UNITED STATES PATENT OFFICE.

TIMOTHY LONG, OF CLEVELAND, OHIO.

HOISTING AND CONVEYING MACHINE.

SPECIFICATION forming part of Letters Patent No. 698,032, dated April 22, 1902.

Application filed January 27, 1902. Serial No. 91,447. (No model.)

To all whom it may concern:

Be it known that I, TIMOTHY LONG, a citizen of the United States of America, and a resident of Cleveland, in the county of Cuyahoga and State of Ohio, have invented certain new and useful Improvements in Hoisting and Conveying Machines, of which the following is a specification.

This invention relates to means for conveying and loading fuel or other material into boats, cars, or other receptacles in a convenient and expeditious manner; and it consists of a boat provided with a number of compartments having slanting bottoms, a longitudinal tunnel connected in the bottom of the boat with the said compartments, a vertical elevator connected with said tunnel, a conveying-drag in the tunnel for conveying the fuel to said elevator.

It also consists of a revolute derrick supported over said compartments, provided with a conveyer and receiving-funnel chute and an adjustable telescopic chute attached to said conveyer capable of adjustment to the several hatchways of a vessel, and suitable power on said derrick-platform for operating said derrick apparatus.

The invention consists in the combination and arrangement of the elements above enumerated, substantially as hereinafter described, and pointed out in the claims.

In the accompanying drawings, Sheet 1, Figure 1 is a side elevation, partly in section, of a boat, showing the aforesaid compartments, elevator, conveyer, and the revolute derrick supported thereon. Sheet 2, Fig. 2 is a vertical section on line 2-2 on Fig. 1, showing the tunnel in the bottom parts of the compartments, also the funnel-chute receiver and the conveyer connected therewith. Fig. 3 is a top or plan view of the apparatus shown in Fig. 1.

A in the several figures represents a portion of a boat.

B B are compartments located in the central part of the boat, the bottoms of which are made slanting toward their centers. C is a tunnel located in the bottom of the boat and connected with each of the said compartments by passing through them and has communication with them by means of doors D D in the sides of the tunnel, whereby one or more of said compartments may be put in open

communication with the tunnel for receiving the contents of said compartments. E is a traveling drag consisting of a belt having scrapers e attached for the purpose of hauling the coal or other material which passes into the tunnel along toward its end and discharge the same to the elevator. The drag is carried by rollers F at the ends. The bottom of the tunnel at the end next to the elevator has a slight inclined rise at C' to connect with the interior of the elevator-casing G. The elevator stands upright at the end of said tunnel C and consists of a bucketed belt H. I is a spout connected with the top end of the elevator-casing G for discharging the material elevated. K is the turn-table of a revolute derrick supported on the deck over the said compartments and near to the said elevator G H.

J J are two upright posts standing at one side the table or platform K, having a cross-head, and is braced by the corner-braces J' J'. M is an adjustable bucketed belt conveyer supported on two beams L L, the lower ends of which are supported on a shaft N, journaled in the posts J J. A sprocket-wheel m, also on said shaft N, carries the belt. O is engine on said platform, connected by gears with the shaft N, by means of which said conveyer is operated. P is a shaft, also journaled in the posts over said shaft N and connected by gear n with gear m'. On said shaft P are provided drums q q, to one of which is attached the rope r, passing up over pulley Q to pulley Q' on the bail R, attached to the beams L L, by means of which the said conveyer M is raised or lowered. To the outer ends of the beams L L is suspended a telescopic spout S by a bail t.

T is a rope attached to one of the drums q, passing over a pulley V on the end of the beam L, thence to a pulley V' on the sliding part of the spout S. By this means the telescopic spout is extended or contracted.

X is an arm on the spout S and has a rope Y attached to its end, by means of which the spout may be turned outward for accommodating it to reach over and to the hatches of other vessels.

Z is a funnel-shaped hopper supported so as to receive the material from the conveyer G H and discharge it onto the conveyer M, by

which it is received and transferred to the spout S. The funnel Z is circular, its center being directly over the center of motion of the turn-table, so that said spout shall always be 5 in position to receive the contents from the spout I, when the derrick may be turned to one side, as represented by dotted lines in Fig. 3.

Having described my invention, what I 10 claim is—

1. In a hoisting and conveying machine, a revoluble derrick, a traveling adjustable conveyer supported and carried by the derrick, a receiving-hopper mounted on the frame of 15 the derrick, and an adjustable telescopic spout attached to the ends of the conveyer-beams, and means for operating the same, in combination, substantially as and for the purpose set forth.
2. In a hoisting and conveying machine, a 20

revoluble derrick, a traveling adjustable conveyer supported and carried by the derrick, a receiving-hopper mounted on the frame of the derrick, in combination with and supported on a vessel having fuel-compartments, 25 a tunnel in the bottom of said compartments, a belted scraping-conveyer in said tunnel, doors in the sides of the compartments for delivering their contents into said tunnel, and a vertical bucketed conveyer connected with 30 said tunnel, and a discharging-spout on the top of said vertical conveyer for transferring material into the receiving-hopper on the derrick, substantially as described.

Signed by me at Cleveland, Ohio, this 25th 35 day of January, 1902.

TIMOTHY LONG.
